UNITED STATES PATENT OFFICE.

JOHN SCHULTZ, OF BRIDGEPORT, CONNECTICUT.

RAILWAY TIE.

Application filed May 16, 1922. Serial No. 561,471.

To all whom it may concern:

Be it known that I, JOHN SCHULTZ, a citizen of the United States, residing at Bridgeport, in the county of Fairfield and State of Connecticut, have invented certain new and useful Improvements in Railway Ties; and I do hereby declare the following to be a full, clear, and exact description of the invention, such as will enable others skilled in the art to which it appertains to make and use the same.

This invention relates to railway ties and particularly to ties of metal construction, and it consists of sheet metal of rectangular construction having closed sides and ends, and is provided with rail clamps projecting through the upper surface of the tie and operated by simple mechanism from within, which mechanism is enclosed by housings 20 and the interior of the tie filled with concrete to give the proper weight and stability to the tie.

Referring to the accompanying drawings in which the several numerals and letters of reference indicate like parts throughout the several views;

Figure 1 represents a railway section equipped with the improved tie;

Figure 2 is a cross sectional view on line 30 2-2 of Figure 1;

Figure 3 is a plan view of the blank from which the tie is formed;

Figure 4 is an enlarged detail central sectional view of the sheet metal tie;

Figure 5 is an enlarged central sectional view of the tie equipped with rail clamps and their operating mechanism;

Figure 6 is an enlarged view of the bottom of the assembled tie;

Figure 7 is an enlarged view of the bottom of an assembled tie filled with concrete;

Figure 8 is an enlarged detail view of one of the rail clamps;

Figure 9 is an enlarged end elevation of 45 the assembled tie, and

Figure 10 is an enlarged detail inside view of one of the end caps.

The tie is formed from the sheet metal blank shown in Figure 3. The sides 1 and 50 ends 2 are bent on the dotted lines *a* and *b* to form the rectangular structure open at the bottom shown in Figures 4, 5 and 6. The upper surface 3 of the tie is preferably thicker than the sides and has the openings 4, 5 and 6, and 7, to admit the body 8 of the

rail clamp whose head 8^a projects above the tie and has the under cut taper lip *c* adapted to engage the taper foot of the rail 9 as well as the taper foot of the fish plates 10, Figures 1 and 2, wherever a rail joint occurs.

The rail clamps are each provided with the notch 12, Figure 8, adapted to fulcrum against the corners 4^a, 5^a, 6^a, 7^a, Figures 4 and 5, of the several openings in the upper surface of the tie. Each tie is provided with four rail clamps arranged in pairs, one pair for each end of the rail, as shown in Figure 1, and each pair is connected and actuated by a bolt 14, Figure 5, whose right hand threaded portion 14^a engages the threaded hole 15, Figure 8, of the outer clamps, while the inner and threadless portion of the bolts bottoms in the recess 16 of the inner clamps. The square ends 17 of the bolts are adapted to receive a socket wrench, not shown, inserted through the square openings 18 in the ends of the ties. Turning the bolts to the right will cause the clamps to rock on their fulcrumed pivots 80 and actuate the bolts in the direction of arrows *d*, *e*, *f*, *g*, to bring the heads of the clamps against the foot of the rails.

The distance between the fulcrums 4^a and 7^a is the same in each tie, and represents the spacing distance between the rails. In other words, these fulcrums being of uniform distance apart, and each clamp being of uniform width on line *h*, Figure 8, the rails will be correctly spaced when the outer edges of the foot of the rails are brought against the inner edges of the outer clamps, as shown in Figure 2.

The housings 19, Figure 6, enclose the mechanism within the tie, and the interior of the tie is filled with the concrete 20, Figure 7, which not only prevents moisture coming in contact with the internal mechanism, but it gives the necessary weight and stability to the tie which the sheet construction 100 would lack but for the addition of the concrete. 19^a is a guide for the bolts 14.

When the ties are properly located and the rail clamps properly adjusted with respect to the rails, the end openings 18 are 105 closed by the cap 21, Figure 6. These caps, Figures 9 and 10, have the square boss 22 adapted to fit the square holes 18 and under spring tension by reason of the kerfs 23. The square recess 24 of the cap will embrace 110

the squared ends 17 of the rail clamp adjusting bolts and thus effectually prevent said bolts turning under the jar of passing trains.

The concrete or other like filling material 5 fills the interior of the tie, surrounding the housings 19 and holding them in place and is a permanent fixture and will not interfere with the operative mechanism, nor prevent such mechanism being removed, if necessary.

10 A tie as above described, is comparatively a simple and cheap construction in consideration of its durability, and when once installed, it remains a permanent fixture. Old rails may be removed and new rails inserted, without disturbing the tie, and when the clamps are once properly adjusted with respect to the rails, such adjustment cannot become accidentally disturbed. Any part of the operative mechanism may be removed 15 without disturbing the position of the tie or interfering with the concrete or other like filling material.

The tie is preferably made of rolled or sheet metal rather than cast metal, as the 20 former is much stronger in proportion to its weight, and will not readily break.

Having thus described my invention what I claim is:—

1. A metal railway tie, having an upper

rail bearing surface, closed sides and ends, 30 said upper surfaces having spaced openings, rail clamps for said openings having a body located within the tie and fulcrumed against the edges of the openings, and a rail engaging head projecting above the tie, a bolt 35 within the tie having a threaded portion engaging a threaded opening in the body of the outer clamp, the inner end of the bolt engaging the body of the opposite or inner clamp to impart a rocking movement to 40 both clamps to and from the rail.

2. A metal railway tie of shell-like construction comprising closed top, sides and ends, said top or upper rail bearing surface having spaced openings, rail clamps operatively fulcrumed therein, a bolt within the tie engaging that portion of the clamps within the tie adapted to adjust said clamps with respect to the rails, said ends of the tie having angular openings, caps therefor having angular bosses for said openings, means connected with said bosses to engage the bolts to prevent their turning, housings for the bolts and clamps, and a filling material covering the housings and filling the interior of 50 the tie.

In testimony whereof I affix my signature.

JOHN SCHULTZ.
